UNITED STATES PATENT OFFICE.

LEWIS M. JONES, OF CHICAGO, ILLINOIS.

DESIGN FOR A BADGE, SEAL, OR EMBLEM.

49,577.

Specification for Design.

Patented Aug. 29, 1916.

Application filed February 12, 1916. Serial No. 78,078. Term of patent 7 years.

To all whom it may concern:

Be it known that I, LEWIS M. JONES, a citizen of the United States, residing at Chicago, in the county of Cook and State of Illinois, have invented a new, original, and ornamental Design for Badges, Seals, or Emblems, of which the following is a specification, reference being had to the accompanying drawing, forming part thereof.

The figure is a plan view of a badge, seal or emblem, showing my new design.

I claim:

The ornamental design for a badge, seal or emblem, as shown.

LEWIS M. JONES.

Witnesses:

WILLIAM G. BENES,
CHARLES B. PAULICET.
